UNITED STATES PATENT OFFICE

FREDERICK E. HORNE, OF MALDEN, MASSACHUSETTS, ASSIGNOR OF ONE-HALF TO
ROBERT BACON, OF WINCHESTER, MASSACHUSETTS

WALL AND UNITS FOR USE THEREIN

Application filed January 9, 1930. Serial No. 419,601.

My present invention relates to a novel wall, constructed of a plurality of individual units, such as shingles, clapboards, or the like, and includes the novel method of laying or constructing said walls, as well as the individual units utilized in connection therewith.

An important object of my present invention is to so assemble shingles or other analogous building units on a wall, that the completed wall will present the appearance of a masonry wall.

Another object of the invention resides in assembling, alternately with the rows of the aforesaid building units, rows or strips of material with sufficient area of said strips exposed below and between each of the first mentioned units to simulate a bond, such as mortar, cement, or any desired medium ordinarily utilized as a bond in masonry construction.

A further object of my invention resides in the utilization, in the aforesaid units and strips, of colors or materials, or both, in simulation of masonry walls, whether brick, tile, cement, stone, terra cotta, or the like.

A further feature of said invention resides in the fact that the building units and bond simulating strips which I utilize will be substantially, if not entirely, equivalent to masonry structures in durability and fire resistance, as well as in appearance, as above explained.

In carrying out my present invention I preferably assemble, on the siding utilized as a base for a wall, shingles, whether single shingles or in strip formation, clapboards or any analogous building material, units or elements, these units being laid in rows, and apply, between each transverse row, a strip of suitable color and material to simulate the appearance of a bond, such as a mortar or cement bond, sufficient of the said strips being exposed between each row of shingles or other units and between each pair of units in a row to create the visual impression of an actual bond.

The color and texture, both of the units and the bond simulating strips, may be of any desired nature whatsoever, and the units

themselves may be constructed to simulate any type of masonry architecture desired, whether standard brick structure, Flemish bond, Dutch bond, stone work, tile work, terra cotta, or any other masonry structure.

For the purpose of simplicity, I have illustrated the wall of the present application as constructed in simulation of a standard brick wall, and although I have illustrated only units in simulation of brick laid in stretcher courses, it will be appreciated that I may vary the shape of the exposed or weather portions of said units to simulate header courses, soldier courses, or the like, it being understood that I do not limit myself, in this application, to any particular style, shape, color, material, design, or any other unnecessary restriction or limitation.

The units which I utilize in my novel wall structure and method of assembly, as well as the bond simulating strips which I alternate with said units, may be of either flexible or rigid construction, I preferably utilizing flexible material as being more economical to construct and lay. The particular base material of which the shingles are formed is irrelevant, as I may utilize wood, asphalt, asbestos, metals of any kind, clay, or combinations thereof.

While a wall constructed according to my present invention will simulate a masonry wall in appearance, exposed texture, weather-proofness, fire resistance and durability, and the like, said wall will be far more economical to construct than the masonry wall of which my wall is a simulation.

The high cost of masonry wall structure is well known. The appearance and fire resisting qualities of such walls, however, is in many instances the prime consideration of the purchaser or builder, and it is, therefore, the aim of my invention to enable a wall to be built in substantially exact simulation of a masonry wall, but at the expense of a shingle or clapboard wall, which is considerably less than said masonry construction.

I believe that a wall constructed according to my present invention, as well as the method of laying or constructing said wall, as well, also, as the units utilized in said wall, are

novel and I have, therefore, claimed the same broadly in this application.

The above and other objects and features of the invention, details of construction and advantages, will be hereinafter more fully pointed out, described and claimed.

Referring to the drawings, illustrating preferred embodiments of the present invention,

Fig. 1 is a fragmentary front elevation of a wall constructed according to my invention;

Fig. 2 is a vertical section on the line 2—2 of Fig. 1;

Fig. 3 is a perspective view of a unit constructed as a strip;

Fig. 4 is a fragmentary perspective view of one of the bond simulating strips;

Fig. 5 is a fragmentary front elevation of a wall constructed according to my invention, utilizing individual units in place of the strips illustrated in Fig. 3;

Fig. 6 is a vertical sectional view on the line 6—6 of Fig. 5;

Fig. 7 is a perspective view of one of the individual units; and

Fig. 8 is a fragmentary perspective view of one of the bond simulating strips of Fig. 5.

Referring now to the drawings, for a particular description of the invention, and the preferred method of carrying out the same, the base of the wall is comprised of studs 10, and siding boards 11, as is usual construction prior to the laying of a shingle or clapboard wall. In carrying out my invention, however, I apply, to said wall, units, preferably in the form of strips, as illustrated at 12, having exposed or weather portions 13, the ends of said strips being provided with a projecting edge 14, defining a notch or cut-out portion 15 of preferably one-half the width of the notches 16. Thus, when the strips of material 12 are abutted in a row, the contacting edges 14 and their notch portions 15 will cooperate to form a full notch 16, and the strips 12 are secured to the siding 11 by nails or tacks 17.

On each row of strips 12 I affix a long strip 18 by means of nails or tacks 19, these strips 18 being of sufficient width to be visible through each notch 16 and also to project slightly below each superimposed row of strips 12.

From a glance at Fig. 1 it will be instantly seen that the completed wall presents a visual appearance in exact simulation of a standard brick wall. This is for illustrative purposes only, as it will be readily understood that the exposed portions 13 of the strips 12 may be of any desired size or shape. It will also be appreciated that the exposed portions 13 may also be of any desired color, texture or coating, to more exactly simulate the wall which it is intended to represent.

It will thus be readily apparent to those skilled in the art that a wall constructed according to my invention will be as economical

to construct as the standard shingle or clapboard walls, while presenting, to all appearances, a visual reproduction or simulation of a masonry wall.

In Figs. 5 to 8 inclusive, I have illustrated 70 the use of individual units 20, rather than strips 12, these units 20 being laid over strips 21, each of the strips 21 being secured to the next lower row of shingles or units 20 by nails or tacks 22, the individual units in turn being 75 attached to the siding 11 by nails or tacks 23. In the construction illustrated in Fig. 5, the units 20 are spaced apart from each other a sufficient distance to simulate a mortar or other uniting bond between each unit 80 20, this appearance being effected by the color and texture of the exposed portions of the strips 21.

The form of wall illustrated in Fig. 5 is 85 as economical to lay or construct as the wall 85 illustrated in Fig. 1, and the utilization of individual units 20 in place of the strips 12 is well within the range of my invention.

My invention is in no way to be confused with the idea or practice of stamping large 90 sheets of metal, or of stamping or printing large plates or strips of roofing material in an attempt to resemble masonry structure. These large sheets or strips, when placed on a wall, will clearly show the outlines of the 95 large sheets, as well as the nails, seams and lapping of the said large strips, and these large units as just briefly described are not satisfactory building materials, either from appearance, desirability, weatherproofness, 10 or the like. Such large sheets will either tear or buckle under temperature changes, whereas small units will not.

While I have necessarily described my present invention somewhat in detail, it will 10 be appreciated that I may vary the size, shape, color, and texture of the various parts, without departing from the spirit of the invention.

My invention is further described and defined in the form of claims as follows:

1. Wall structure, comprising a plurality of rows of shingle-like units, and a separate row of material interposed between adjacent rows of units, the units in each row being 11 spaced apart a distance substantially equivalent to a standard vertical mortar course, said rows of material being arranged with respect to adjacent rows of units to expose a portion of said row of material substantially equivalent to a horizontal mortar course, whereby the completed wall will simulate a masonry wall with mortar courses between the units thereof.

2. Wall structure, comprising a plurality 12 of rows of shingle-like units, and a separate row of material interposed between adjacent rows of units, the units in each row being spaced apart a distance substantially equivalent to a standard vertical mortar course, said 13

rows of material being arranged with respect to adjacent rows of units to expose a portion of said row of material substantially equivalent to a horizontal mortar course, the exposed surfaces of said units and said material being of contrasting color, whereby said wall will simulate a masonry wall with mortar courses between the units thereof.

3. Wall structure, comprising a plurality of rows of shingle-like units, and a separate row of material interposed between adjacent rows of units, the units in each row being spaced apart a distance substantially equivalent to a standard vertical mortar course, said rows of material being arranged with respect to adjacent rows of units to expose a portion of said row of material substantially equivalent to a horizontal mortar course, the exposed surfaces of said units and said material being of contrasting color and textures, whereby said wall will simulate a masonry wall with mortar courses between the units thereof.

In testimony whereof I have signed my name to this specification.

FREDERICK E. HORNE.
